UNITED STATES PATENT OFFICE.

MARSHALL C. LEFFERTS, OF NEW YORK, N. Y., ASSIGNOR TO THE ELECTRIC CUTLERY COMPANY, OF NEWARK, NEW JERSEY.

DESIGN FOR A HANDLE FOR RAZORS.

SPECIFICATION forming part of Design No. 20,997, dated August 18, 1891.

Application filed July 18, 1891. Serial No. 399,411. Term of patent 7 years.

To all whom it may concern:

Be it known that I, MARSHALL C. LEFFERTS, a citizen of the United States, residing in the city of New York, in the county and State of New York, have invented and produced a new and original Design for Handles of Razors, of which the following is a specification, reference being had to the accompanying drawing, illustrating my design.

My design consists of an open-work design, resembling the intertwining of somewhat vine-like forms, apparently held together by a cord penetrating one end of the handle.

The open-work permits the razor-blade when closed to be seen through the perforations of the handle, and thus exhibits the ornamentation of the blade.

What I claim is—

The design for handle ornamentation, consisting of the open-work design, substantially as shown.

MARSHALL C. LEFFERTS.
